Patented Feb. 13, 1917.

UNITED STATES PATENT OFFICE.

HENRY B. RUGGLES, OF CHICAGO, ILLINOIS.

KNOCKDOWN BOX.

1,215,713.

Specification of Letters Patent. Patented Feb. 13, 1917.

Application filed January 2, 1914. Serial No. 809,896.

To all whom it may concern:

Be it known that I, HENRY B. RUGGLES, citizen of the United States, residing at Chicago, in the county of Cook and State 5 of Illinois, have invented certain new and useful Improvements in Knockdown Boxes, of which the following is a specification.

This invention pertains to improvements in box construction, and more especially to 10 knock-down or collapsible boxes.

The chief objects of the particular improvements embodied in this application, are:—the economical production of a collapsible box from a combination of fiber or 15 pulp-board and wood members, or from all-fibrous material; the provision of means whereby the parts may be quickly assembled either by the box manufacturer or by the user of the boxes; the provision of simple, 20 inexpensive and efficient means for connecting the sides to the ends of the box, and a construction by which a box used in transporting goods may be converted into a container adapted to display the contents.

25 In the accompanying drawings I have illustrated a preferred embodiment of my invention in the following views:—

Figure 1 is a perspective view of a box made according to my invention;

30 Fig. 2 is a view partly in section, and partly in perspective, showing corresponding corners of the upper and lower portions of a box constructed according to my invention;

35 Fig. 3 is an enlarged sectional view, showing one method of connecting the side and top walls of my improved box;

40 Fig. 4 is an enlarged fragmentary sectional view showing another method of connecting the side walls and top of my improved box, and—

45 Fig. 5 is an enlarged sectional view of the construction shown in Fig. 2 with a different form of cover member designed to protect the transparent member.

50 Referring to the details of my invention, the reference characters 6 and 7 represent respectively, the upper and lower frames which form the rims of the top and bottom of my improved box, to which frames or rims are fitted the side wall members 8 which are reinforced where bent to provide corners, by strips of fabric or other suitable material, as indicated by the reference character 9 in Fig. 1. Fitted within the frame 6

is shown a supplemental lock or inner frame 10, the outer walls of which are fitted to the inner walls of the frame 6, and a similar frame 11 is applied to the bottom frame 7.

As shown in Figs. 2 and 5, 12 represents a 60 sheet of glass, mica, or other transparent material, the edges of which are secured to the lower face of the supplemental frame 10.

13 represents a sheet of pulp or fibrous material which, as shown in Fig. 2, is secured to the under side of the outer frame 6, 65 nails being used to attach said member 13 to said frame 6.

As shown in Fig. 3, the sheet 13 has its margins bent up at right angles to form 70 flanges 13^b which are adapted to enter kerfs 6^b formed in the frame member 6. These kerfs are preferably formed tapering outwardly from their bottoms with the mouth rounded as shown at 6^c, Fig. 5, such an enlarged mouth and tapering wall kerf facilitating the entrance of the margins of the side walls 8. The side walls 8 are preferably formed with apertures 8^a along their edges which receive the glue or other adhesive which is placed in the kerfs 6^b in sufficient quantities so that when the margins of the walls 8 are pushed into said kerfs the sealing adhesive substance will flow into the openings 8^a and thus form when set or hardened efficient anchoring means for holding 80 said side walls securely in place relative to the frame members 6 and 7. Similar openings will be provided in the flanges 13^b of the cover member 13 when the form of my 85 invention illustrated in Fig. 3 is adopted. The cover member 13 is preferably provided with a score line 13^a at the inner margin of the frame member 6, so as to facilitate the severance of a portion of the member lying 90 within the frame when it is desired to open the box.

In Figs. 3 and 4 I have indicated the frame members as made from fibrous material, such as wood pulp, in which case the members including the kerfs would be formed in suitable molds or by dies.

100 In Fig. 4 I have indicated one method of closing the mouth of the kerf, and at the same time securing the margin of the side wall 8 within the kerf by upsetting or pressing inwardly the outer portion of the wall of the frame member 6 which flanks the kerf 6^b on the outer side of the frame. When thus deformed there will be a recess 105 110

6° at one side of the margin of the member 8, and if desired this may contain the sealing adhesive above referred to.

While ordinarily the top and bottom 5 frame filling members 13 and 14 will be in separate sheets secured as shown in Figs. 2 or 3, I may form said members integral with the frame members 6 or 7, as indicated at 13°, Fig. 4. This can readily be done 10 where the material used in the manufacture of said members is a fibrous pulp adapted to be molded or pressed into any desired shape.

I prefer to make the interfitting walls 15 of the members 6 and 10, and 7 and 11, with broken joints as indicated at 6°, 10°, and 7°, 11°. The members 10 are preferably secured to the members 6 by light nails which may be easily removed when it is desired to disconnect the two frames. This operation is 20 resorted to when the user of the box wishes to convert it into a display container which is readily done by cutting out the portion of the cover 13 within the scored lines 13°, and then replacing the frame 10 with its 25 transparent member 12. When thus replaced the frame 10 will rest removably upon the frame 6, the shouldered or broken joint serving as an effective support for the inner frame. When it is desired to protect 30 the transparent member 12 in the shipment of the box supplied with such member, I will use a sheet of fiber the margins of which will be bent up at right angles as at 15, Fig. 5, and the same nails which secure the 35 frame 10 to the frame 6 will pass through said flanges and hold the member 15 in place until the box reaches the hands of the user when the member 15 may be readily removed by withdrawing the nails. In such 40 case I may dispense with the cover member 13 on the under side of the transparent member 12.

From the construction illustrated and above described, it will be obvious that I 45 have provided a container the members of which can be completely formed at a central manufacturing plant, can be shipped to the user who can assemble the parts quickly and easily with the use of but few nails or brads, 50 and who can lock the top and bottom members to the sides by merely pouring a suitable adhesive substance into the kerfs formed in the top and bottom frames, and that when the box thus assembled is packed or filled 55 any attempt to open it will require either the severance of the top or bottom walls 13, 14, from their respective frames or the fracture of the hard sealing medium used

in the kerfs and portions of which, as we have seen, will fill the apertures 8°, thus disclosing that the package has been tampered with.

It is also obvious that I may add as many braces or cleats to my improved box as the size or uses to which it is to be put would indicate desirable for the purpose of giving greater strength and rigidity to it. Where the cover member 13° is made integral with the frame member 6, I may form the same kerf 13° to indicate the cutting line where 70 it is desirable to separate the central portion of said member 13° from the marginal portion.

While I have shown and described a rectangular box or container constructed according to my invention, it will be obvious that all of the features thus shown and described are equally applicable to a cylindrical or other shaped container, hence I do not wish to be understood as limiting my invention to a rectangular box as the shape is no part of my invention. The corner strips may be flexible so that the sides can lie flat when not assembled with the cover members, or they may be of such material as to make a rigid structure at the corners. In this connection I have shown the members 9 as a thin flexible material pasted to the side members 8 and serving merely as flexible hinges for said members.

Having thus described my invention what I claim is:—

1. A container composed of top and bottom frames having tapering kerfs therein, sheets of fibrous material secured to the inner surfaces of said frames, and adapted to form the top and bottom walls of said container, other sheets of fibrous material having perforated margins extending within the tapering kerfs and forming the sides of said container, and means for sealing said perforated margins within said kerfs.

2. In a container, end frames having tapering kerfs therein, collapsible side walls having perforated margins adapted to fit within said kerfs, and means for securing said margins therein consisting of a flux adapted to flow into said kerf and pass through said perforations, there to set and harden.

In testimony whereof I affix my signature in the presence of two witnesses.

HENRY B. RUGGLES.
